United States Patent Office.

WILLIAM FARSON, OF PHILADELPHIA, PENNSYLVANIA.

Letters Patent No. 98,858, dated January 18, 1870.

IMPROVED SOFA-BEDSTEAD.

The Schedule referred to in these Letters Patent and making part of the same.

I, WILLIAM FARSON, of the city of Philadelphia, and State of Pennsylvania, have invented certain Improvements in Sofa-Bedsteads, of which the following is a specification.

The nature of my invention mainly consists of a combination of catch-levers with a hinged bar, to which supplemental feet are attached, for the support of the back of the sofa, when lowered, to receive the bedding, in such a manner that when the back is raised and brought against the vertical back edges of the arms of the sofa, and the bar is turned against the back of the same, the said lever-catches are brought into connection with stops in the back vertical edges of the arms, so as to hold the back securely in place; and when the back has to be lowered into a horizontal position, for the reception of the bed, by turning the bar so as to bring the said supplemental feet at right angles to the back, for the support of the same, the catches are disengaged.

It further consists in a hinged part of each end of the sofa, at the inside of the same, in such a manner, that when the back is lowered to its horizontal position, said parts may be swung around in straight lines with the standing parts, to complete the head and foot-boards, the inside and outside of the ends of the sofa, and the swinging parts being made alike, so as to correspond.

The improvement also consists in such a construction of the hinged catches, that they shall be made to lock the hinged portion of the arms in their backward position.

To enable others skilled in the art to which my improvement appertains, to make and use my invention, I will now give a detailed description thereof.

In the accompanying drawings, which make a part of this specification—

Figure 1 is an isometrical view of the improved sofa-bedstead.

Figure 2 is a cross-section at the middle of the same.

Figure 3 is a cross-section, between the standing arm G and the swinging part G', at the near end of the sofa.

Like letters, in all the figures, indicate the same parts.

A. is the lower portion of the sofa, which has a space, a, for the reception of the bed-clothes, the cushioned bottom C being connected by means of the hinges b, to the longitudinal strip D, so as to admit of its being thrown upward, and held by means of springs, or in any other convenient manner, when the clothes are to be removed or replaced.

The back E is connected, at its lower edge, to said strip, by hinges c, so as to admit of being brought into a horizontal position, as represented in fig. 2, to form the back portion of the bed-bottom, the bar F

turning on its hinges d. When said bar is turned one-fourth round, to bring the supplemental feet e e in connection therewith, at right angles to the back, for the support of the same, the arms of the sofa have a vertical division.

At each end there is a standing part, G, to which is hinged a swinging part, G', the hinges f f connecting the vertical edges g together, as seen in figs. 1, 2, and 3, so that when the inner parts G' G' are swung backward, as represented in fig. 2, over the back E, they form head and foot-boards to the same.

The said parts G' G' are made to constitute inner portions of the ends of the sofa, so as not to require additional space for swinging them backward and forward, for the purpose of accommodating the sofa to any recess it can be set in.

The back E, when in its upward position, has an outward inclination given to it, by means of the angle-pieces h h, fast to the same, which fit against the back edges of the ends G G of the sofa, and swinging parts G' G'. It is held securely in said position by means of the lever-catches H H, which have a joint connection, by means of the slotted straps I I and pins i i, the fulcrum-pins j of the levers passing through the cheeks k of said angle-pieces, between which the levers play, the operation of said lever-catches being as follows:

When the back is turned up into the position it assumes in figs. 1 and 3, the bar F still remains at right angles to the same, as represented by dotted lines, and the catches l of the lever, being thrown outward, they pass over the upper ends of the knuckles of the hinges, and by turning the bar, so as to bring it and the feet e e into a vertical position, and against the back E, the catches l are brought into connection with the knuckles of the hinges, as represented in full lines, so as to lock the back in place.

When the back has to be turned, to bring it into the position represented in fig. 2, the bar F is again turned at right angles with the same, and into the former position, represented by dotted lines, and the catches are disconnected, to admit of the change.

The swinging parts G' G' of the ends of the sofa are then turned into the position they assume in fig. 2, and back of the catch-ends of the levers H H, so as to be held securely in their outward position, their vertical back edges being thus brought against the edges of the standing part G G, and thus kept from going outward. Spring-catches, beneath the edges of the parts G' G', may be used to hold them back.

If the joints of the swinging arms G' G' should, by being strained or worn, prevent the perfect closing of the latter against the standing parts G G, I design placing of India rubber, in suitable holes in the

edges *g g* of said arms, so that when the back *E* is brought into its upper position, by bearing upon said pieces of rubber, the arms shall be brought against the standing parts *G G*.

What I claim as my invention, and desire to secure by Letters Patent, is—

The combination of the catch-levers *H H*, with the feet-bar *F*, arranged in relation to the hinges *f*, or other stops, as above specified, so as to lock and unlock the

back *E* by the changes in the position of the said bar, substantially in the manner hereinbefore described.

In testimony that the above is my invention, I have hereunto set my hand, and affixed my seal, this 2d day of December, 1869.

WILLIAM FARSON. [L. S.]
